UNITED STATES PATENT OFFICE.

ERNEST R. VIBERG, OF MONTREAL, QUEBEC, CANADA.

ANGLE-COCK HOLDER.

1,174,781.

Specification of Letters Patent.

Patented Mar. 7, 1916.

Application filed June 9, 1914. Serial No. 844,045.

To all whom it may concern:

Be it known that I, ERNEST R. VIBERG, a citizen of the Dominion of Canada, residing at the city of Montreal, in the Province of Quebec and Dominion of Canada, have invented certain new and useful Improvements in Angle-Cock Holders, of which the following is a full, clear, and exact description.

This invention relates to improvements in angle cock holders, and the object is to provide a simple, inexpensive and reliable device which will hold the angle cocks at the ends of the air and steam pipes under a car against revolution and consequent leakage or loss.

A further object is to provide a device which will support the air or steam pipes at the extreme end, and hold the angle cock in the desired position relative to other parts of the car.

The device consists essentially of a single member having a pocket for the reception of the polygonal portion of the angle cock, communicating at the rear with an opening for the passage of the pipe to which the angle cock is attached. The angle cock is inserted in the pocket through a lateral passage, so that when once in the pocket, it cannot move in the longitudinal direction of the car, and is held against lateral movement out of the pocket by the pipe to which it is attached passing through the back of the pocket.

In the drawings which illustrate the invention:—Figure 1 is an end elevation of the device, the angle cock and pipe being removed. Fig. 2 is a side elevation showing the pipe and angle cock in broken lines. Fig. 3 is a section on the line 3—3, Fig. 1.

Referring more particularly to the drawings, 5 designates the end sill of a car, 6 a steam or air supply pipe, and 7 the angle cock connected thereto. The holder forming the subject of this invention consists preferably of a single member, which may conveniently be in the form of a malleable casting. This member comprises a base 9 riveted or otherwise secured to the end sill, and having at the outer end thereof a perpendicularly depending plate 10 of suitable shape. On the outer surface of this plate, a wall 11 is provided having an inwardly projecting flange 12. This wall and its flange, together with the plate 10, form a pocket 13 for the reception of the polygonal portion 8 of the angle cock, which is usually hex-

agonal. The wall 11 may thus be described as consisting of upper and lower horizontal portions and two intermediate portions on the side adjacent the center line of the car 60 arranged at an angle of 120° to one another and to the upper and lower wall portions. The wall thus forms four sides of a hexagonal pocket, the two remaining sides which are adjacent the side of the car being 65 omitted to permit the insertion of the angle cock in a lateral direction. The flange 12 is preferably circularly curved at its edge in place of following the hexagonal form of the wall 11, so that it will closely embrace 70 the neck of the angle cock adjacent the polygonal portion thereof. The upper end of the wall 11 is turned upwardly at an angle of approximately 120°, and preferably tapers down from the full height of the wall 75 to nothing at the base, so as to form a stiffening and supporting rib 14 for the plate 10. The plate 10 is provided with a circular aperture 15 for the passage of the pipe 6, this aperture being arranged concentric 80 with the pocket 13. On the inner side of the plate 10, the pipe aperture 15 is surrounded by a flange 16 of suitable depth, from which a stiffening rib 17 extends to the base, this rib being preferably arranged 85 in the same plane as the rib 14, as clearly shown in Fig. 1. It will be noted in the drawings that the plate 10, while arranged in a plane perpendicular to the base, extends in an angular direction in said plane, so that 90 the lower end of plate is nearer the center line of the car than is the base. This enables the base to be secured to the end sill far enough to one side to be clear of the draft gear or buffer, and yet carry the pipe 95 as close as possible to the center of the car.

In building the cars, the holders are secured to the end sill thereof in suitable position with the pocket openings facing away from the center line of the car. The 100 polygonal end of the angle cock is then inserted in the pocket, and the pipe 6 passed through the opening 15 and screwed into the angle cock, which is held against revolution by the holder. It will be readily understood that no amount of swinging or jerking of the air hose can loosen the cock on the pipe and permit leakage or eventual loss of the cock. Furthermore, the angle cocks are held in such a way that they cannot be stolen without great difficulty, and 110 cannot be wrenches off if the air or steam is

accidentally left coupled when the cars are uncoupled.

While the device has been shown of a particular form and described as consisting 5 preferably of a malleable casting, it is obvious that by slight variation in form, the device may be made of drop forgings or stamped sheet. In either of these cases, it will be preferable to divide the holder into 10 two parts on the plane of the supporting ribs 14 and 17, which will be carried by each part and will form flanges for connecting the parts together. In this case, the ribs may also be extended at the lower end of 15 the holder for the same purpose.

Having thus described my invention, what I claim is:—

1. A device of the character described, comprising a base, an apertured plate perpendicular thereto, a flanged wall projecting from one side of said plate forming a polygonal pocket open at the side, a collar on the opposite side of said plate surrounding the aperture thereof, a stiffening rib 25 for the plate extending between the collar and base, and a stiffening rib on the opposite side of the plate tapering from the upper end of the pocket wall to the base and lying in the same plane as the first 30 mentioned rib.

2. A device of the character described, comprising a base, a plate depending angularly therefrom in a plane perpendicular to the base, said plate being apertured at its 35 lower end for the passage of a pipe, a collar

surrounding the pipe aperture of said plate, a rib extending from said collar to the base, a wall projecting from the opposite side of said plate formed to engage the polygonal end of a cock screwed on said pipe and hold 40 the same against revolution, and a flange projecting from said wall having the edge thereof circularly curved to embrace the neck of said cock adjacent the polygonal portion thereof and hold the pipe against 45 longitudinal movement through the plate.

3. A device of the character described, comprising a base, an apertured plate depending from one edge of said base in an angular direction and in a plane perpendicular to the base, a flanged wall projecting from the opposite side of said plate from the base forming a pocket concentric with the plate aperture arranged to embrace the polygonal portion of an angle cock and 55 hold the same against revolution and movement away from the plate, a rib extending from the pocket wall in a direction parallel with the angular direction of the plate, a collar surrounding the plate opening on the 60 opposite side thereof from the pocket, and a rib extending between said collar and the base in a direction parallel with the angular direction of the plate.

In witness whereof, I have hereunto set 65 my hand, in the presence of two witnesses.

ERNEST R. VIBERG.
